METHOD OF MAKING STRUCTURAL UNITS

Fred F. Becker, Chicago, Ill., assignor, by mesne assignments, to Rock-Ola Manufacturing Corporation, Chicago, Ill., a corporation of Delaware

Application February 27, 1935, Serial No. 8,428

2 Claims. (Cl. 113—116)

This invention relates to a structural unit and method of making the same.

It is an object of this invention to provide an improved structural unit which is relatively simple and inexpensive in construction and efficient in use.

Another object of this invention is to provide an improved structural unit, which is adapted to be mounted upon an arm, shaft, or other supporting member; and the present invention is particularly concerned with providing a new method for aligning holes or apertures in the structural unit for the reception of a supporting arm, shaft, or other supporting member.

15 Other objects will appear hereinafter.

The invention consists in the novel method and in the novel combination and arrangement of parts to be hereinafter described and claimed.

The invention will be best understood by reference to the accompanying drawing, showing a preferred form of construction for the new structural unit and in which:

Fig. 1 is a perspective view illustrating a preferred form of the new structural unit in position of use;

Fig. 2 is a sectional view on line 2—2 in Fig. 1;

Fig. 3 is a perspective view showing a preferred form of the new structural unit as it appears in the blank form, that is, prior to the forming operation;

Fig. 4 is a perspective view showing the new structural unit in the process of formation; and

Fig. 5 is a vertical sectional view showing the new structural unit during the forming operation.

35 A preferred form of the new structural unit is shown in the drawing, is therein generally indicated at 10, and is adapted to be mounted upon a supporting arm, shaft, or member 11, for any desired purpose, such, for example, as is illustrated in Fig. 1, wherein the unit or member 10 is shown provided with a slot 13 which is adapted to receive a roller 14, the roller 14 being designed to operate a movable element 12 of a machine, device, or apparatus of any desired construction.

45 As shown in Fig. 3, the new structural unit or member 10 is formed from a body or piece of flat metal stock 15, and the first step in forming the unit 10 is the provision in the body or stock 15, adjacent one end thereof, of spaced apertures 50 or openings 16.

The present invention is particularly concerned with the provision of a new method for forming the new structural element or unit 10 in such a manner that the openings or apertures 16 there-

the forming operation, to receive supporting shaft or member 11 upon which the structural element 10 is intended to be mounted and used after the completion of the forming operation.

In the manufacture of the new structural unit 5 10 there are provided in the end portion 17 of the stock or body 15, on opposite marginal edges thereof, notches 18 which provide, in effect, a line of weakened union 19 which extends transversely across the stock or body 15 relative to 10 the long axis of the same; these notches 18 being provided in the stock 15 either simultaneously with the formation of the apertures 16 or before or after that operation, as desired.

The end portion 17 of the structural unit 10 15 is then bent back upon itself, along the line of weakened union 19 by means of a forming die, as follows: the body or stock 15 is placed upon the bed 20 of a suitable forming die or press, above an opening 22 which is formed in the bed 20 of the press, and within an opening 23 which is provided in the bed plate 24; the bed plate 24 being mounted upon the upper surface of the bed 20 of the die or press so as to hold the stock 15 in a stationary position, and against lateral 25 or longitudinal displacement, during the forming operation.

The bed plate 24 is provided with an elongated slot 21 and during the forming operation the die 25 is pressed down upon the end portion 17 30 of the stock 15, along the line of weakened union 19, and with the jaws 26 of the forming die projected through the slot 21 on opposite sides of the stock 15, into the well 22 of the bed plate 20; the jaws 26 of the forming die passing into 35 corresponding lateral openings 27 formed in the bed 20 of the die in communication with the well 22. In this manner the end portion 17 of the stock 15 is bent back upon itself into a substantially U-shaped formation, as shown in Figs. 1, 40 2 and 5, thereby providing a portion 28 which extends substantially parallel to the main extent or body of the member 17, in spaced relationship thereto.

It will be noted that during the forming opera- 45 tion the jaws 26 of the forming die hold the stock 15 relatively immovable in the recess 23 in the bed plate 24 of the die, that is, against lateral or longitudinal displacement, so that the stock 15 can not twist or turn and hence the opening or 50 apertures in the stock 16 are properly aligned and registered for the reception of the supporting shaft or member 11, as shown in Figs. 1 and 2, and in this manner the unit is made from a single piece of stock rather than being assembled 55.

from separate parts or being made by drilling a hole through a piece of heavy stock for the reception of the supporting shaft 11.

To complete the operation and so as to hold the completed unit 10 in a relatively fixed position upon its supporting shaft or member 11, a transversely extending groove 29 is provided in the peripheral surface of the supporting shaft or member 11, as shown in Fig. 2, and a pin 30 is inserted into this groove 29 and between the opposite arms of the U-shaped portion of the structural element 18-15, so as to latch the same in a relatively fixed position upon its supporting shaft or member 11, thus completing the assembly of the new structural unit.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such

variations and modifications as come within the scope of the appended claims.

I claim:

1. The method of making a structural unit of elongated form which comprises cutting an elongated blank, drilling spaced holes in said blank, cutting opposite edgewise notches in the blank midway between the axes of said holes, and forcing said blank into a well having rigid side walls by application of pressure against said blank between said notches, while utilizing said notches in effecting axial registration of said openings.

2. The method of making a metal structural unit which includes forming an elongated blank of thin metal, drilling spaced openings in said blank between its longitudinal extremities, notching the opposite longitudinal sides of said blank between its ends midway between the axes of said openings, and bending said blank along a line between said notches into a U-shaped member while utilizing said notches in effecting axial registration of said openings.

FRED F. BECKER.
